FASTENER

Elmer L. Zwickel, Chicago, Ill., assignor to Acco Products, Inc., Long Island City, N. Y., a corporation of New York

Application April 4, 1933, Serial No. 664,355

15 Claims. (Cl. 24—153)

The invention relates to improvements in fastening devices and particularly to an improved fastener for binding papers together, of the type including a base having spaced prongs on its ends 5 adapted to extend through apertures in the papers and through spaced openings in a compressor having improved means to retain the said prongs bent over said compressor.

An object of the invention is to provide a 10 fastener of the character described comprising separable parts having improved means for securing said parts together.

Another object is to provide a loose-leaf fastening device including a base having spaced 15 prongs adapted to extend through apertures in the sheets of paper to be bound and a compressor having improved yieldable means to urge and hold the portions of the prongs extending through openings therein over and against said compressor.

Another object is to provide a fastener of the character referred to with a compressor having improved means adjacent each end to hold 20 prongs, extending through openings therein, bent over and against the compressor.

Another object is to provide a fastener of the character referred to with improved means for semi-automatically bending portions of prongs 25 extending through the compressor over and against the compressor.

Another object is to provide a fastener of the character referred to with improved means for holding prongs locked against the compressor, which may readily be released to facilitate 30 disengagement of the parts.

The foregoing and such other objects of the invention as will appear hereinafter as the description proceeds, will be more readily understood from a perusal of the following specification, reference being had to the accompanying drawings, in which:

Fig. 1 is an enlarged perspective view of one form of the improved fastener.

Fig. 2 is a side elevational view of the improved 45 device, showing a part of the compressor and one of the locks in section.

Fig. 3 is a transverse sectional view, taken on line 3—3 of Fig. 2.

Fig. 4 is a view similar to Fig. 3, showing the 50 lock and prong raised.

Fig. 5 is a fragmentary plan view of a compressor having a modified form of locking means thereon.

Fig. 6 is a sectional view, taken on line 6—6 55 of Fig. 5.

Fig. 7 is a fragmentary perspective view of the compressor shown in Fig. 5.

Fig. 8 is a view similar to Fig. 5, showing a modified form of lock.

Fig. 9 is a plan view of a fastener, showing 5 yieldable means for locking the prongs bent against the compressor.

Fig. 10 is a fragmentary longitudinal sectional view of the fastener shown in Fig. 9, illustrating 10 the initial position of a prong after having been inserted through the opening in the compressor.

Fig. 11 is a fragmentary longitudinal sectional view similar to Fig. 10, showing the prong bent over and held against the compressor.

Fig. 12 is a sectional view, taken on line 12—12 15 of Fig. 9.

Fig. 13 is a plan view of the compressor, illustrating another form of lock.

Figs. 14 and 15 are fragmentary plan views of 20 other modified forms of compressors and locks.

Fig. 16 is a transverse sectional view, taken on line 16—16 of Fig. 15.

Fig. 17 is a fragmentary longitudinal sectional view of a compressor and lock.

Fig. 18 is a fragmentary plan view of another 25 form of compressor and lock.

Figs. 19, 20 and 21 each illustrate a further modification of the compressor and lock.

Fig. 22 is a transverse sectional view, taken 30 on line 22—22 of Fig. 21.

Fig. 23 is a perspective view of another form of fastener.

Fig. 24 is a fragmentary plan view of a fastener, showing another lock.

Figs. 25 and 26 are fragmentary plan views of 35 a fastener, having modified forms of locking means thereon.

Fig. 27 is a fragmentary longitudinal sectional view, taken on line 27—27 of Fig. 26.

Figs. 28, 29, 30, 31 and 32 are fragmentary 40 plan views of different fasteners, each having a modified form of locking device thereon.

The improved fastener preferably includes a base 11 having prongs 12, one at each end, bent 45 at right angles thereto and arranged to extend through spaced apertures in the papers 13 to be bound. A compressor 14 is adapted to be placed over the papers 13 with the projecting ends of the prongs 12 extending through suitable spaced lateral openings 15 provided one adjacent each end of said compressor. The extended ends of the prongs 12 are bent over preferably inwardly against the compressor and are adapted to be held in this position by suitable locks 16 arranged 50

55 of Fig. 5.

one at each end of the compressor adjacent each opening 15.

In the fastener illustrated in Figs. 1 to 4, inclusive, the locks 16, preferably formed of sheet metal, have an intermediate portion 17 and parallel leg portions 18. Each leg portion 18 has an outwardly directed lug or bearing 19 to engage in an opening 21 in reinforcing beads 22 provided one on each longitudinal edge of the compressor 14. The beads 22 preferably are formed by rolling the edges of the compressor. The beads 22 also have a plurality of spaced inwardly directed lips 23 above the top plane of the compressor for co-operation with the intermediate portion 17 of the locks after the latter have been swung downwardly over the top of the bent down prongs 12, to retain said locks in position.

The intermediate portion 17 of each lock may be formed with a finger-engaging portion 24 to facilitate disengagement of the lock from lips 23 whereby said prongs and the locks may be moved into a substantially vertical position to allow removal of the compressor 14 from over said prongs. When the locks 16 are substantially vertical, a projection 25 provided on the end of each leg portion 18 frictionally engages in a detent 26 in the compressor, thus holding the locks in position to receive the prongs 12 through the spaced openings 15 upon placing the compressor over the paper.

The prongs 12 also may be bent outwardly of the apertures, and said prongs are held bent down against the compressor by co-operation of the intermediate portion 17 of the locks 16 with the lips 23 in the beads 22 outwardly of said apertures 15.

Figs. 5 to 7, inclusive, show a modified form of lock 16a, said lock being substantially T-shaped with an enlarged bearing portion 27 formed to receive inwardly turned aligned bearings 28 formed in the reinforcing beads 22a. The lock 16a has a lug 29 thereon for engagement with an aperture or detent 31 in the compressor for retaining the lock substantially vertical, as illustrated in dotted lines in Fig. 6. When the lock 16a is turned downwardly over prongs 12, said lock engages yieldingly detents 32 provided in bead 22a, whereby the prong is securely held bent down against the compressor 14a.

The lock 16b illustrated in Fig. 8 is substantially like the lock shown in Fig. 1. However, in this instance, an inwardly directed lug 33 is provided on the end of each leg portion 18b for insertion into a bearing 34 formed by rolling the material cut from the compressor 14b to provide the lateral opening 15b.

The compressor 14c illustrated in Figs. 9 to 12, inclusive, has reinforcing beads 22c and spaced lateral openings 15c for receiving the prongs 12. Extending upwardly outwardly of and adjacent each opening 15c, between the beads 22c, is a flange or lip 35 cut away, as at 36, to provide bearing pintles 37 to receive the coiled ends 38 of locks 16c formed of spring steel wire and adapted normally to lie tightly against the compressor. While passing the prongs 12 through the openings 15c, the locks 16c are urged upwardly, as in Fig. 10, against the action of the coiled ends 38. The resistance of the spring locks tends to turn the projecting ends of the prongs inwardly. When the compressor is in its proper position over the prongs, pressure is applied momentarily to the locks 16c to force 75 the prongs flat against the compressor 14c.

Movement of the prongs upwardly away from the compressor is prevented by the yieldable locks 16c, thus the compressor is held tightly against the papers bound thereby.

The compressors 14d shown in Figs. 13 and 14 each are provided with locks 16d substantially like locks 16, illustrated in Fig. 1. However, these locks are mounted outwardly of the openings 15d to allow inwardly folding only of the prongs 12.

The locks 16e illustrated in Figs. 15 and 16 are, in form, substantially like locks 16d. Each is made of a length of wire having its ends 39 journaled in the reinforcing beads 22 on the compressor. The outwardly turned curved ends 41 of the locks co-operate with detents 42 in the beads 22 to retain the intermediate lock portion 43 tightly over and against the underlying prong 12.

The lock 16f in Fig. 17, has a squared bearing portion 44 journaled in the split bearing opening 45 provided in the bead 22f. The split bearing 45 holds the lock yieldingly in either raised or lowered position.

A spring clamp 46, shown in Fig. 18, retains 25 the prong 12 against the compressor. This spring clamp preferably is secured intermediate its ends in the folded over longitudinal edges 22g of the compressor.

The compressors illustrated in Figs. 19 and 20, 30 have their longitudinal edges reinforced by upwardly directed flanges 47. The compressor 14h shown in Fig. 19, has inwardly directed lips 48 on its upturned flanges 47 for co-operating with the locks 16h which, are journaled on the longitudinal axis of the openings 15h, whereby the prongs 12 may be folded inwardly or outwardly of the apertures and securely locked against the compressor in either position.

The lock 16i on the keeper 14i, illustrated in Fig. 20, is adapted to co-operate with lips 49 extending upwardly from the compressor inwardly and outwardly of the opening 15i on either side of prong 12.

The compressor 14j shown in Figs. 21 and 22 has an opening 15j to receive prong 12 which is adapted to be bent down against the compressor and securely held by a lock 16j. The lock is pivoted to one side of the opening 15j and has oppositely directed lips 51 to frictionally engage the prong 12, irrespective of whether said prong is bent inwardly or outwardly of the opening 15j against the compressor.

The compressor 14k (Fig. 23) has its longitudinal edges folded inwardly over the top surface thereof to provide flat reinforcing beads 22k. The beads 22k are raised midway between the spaced openings 15k to receive the oppositely disposed bearing portions 52 provided on one end of each lock 53. The other end of each lock 60 has a cross-head 54 adapted to co-operate with spring lips 55 in beads 22k when said locks are folded down over prongs 12. Retention of the locks 53 either against the compressor or in vertical or substantially vertical position is obtained by the yielding co-operative engagement of the squared bearing portions 52 with the substantially square raised bearings 56 of the beads 22k.

The locks 57, shown in Fig. 24, preferably are made of spring steel and adapted to be held manually in a raised position prior to the bending of the prongs therebeneath. Each prong is slotted longitudinally to receive a detent 58 on the end of each lock 57, whereby the locks and 75

the prongs are frictionally and yieldably held together to prevent displacement of the compressor.

5 The wire lock 161 shown in Fig. 25 is formed at 59 to engage frictionally the detents 61 formed in the side walls of the beads 221.

Figs. 26 and 27 show the compressor 14m provided on each end with a rolled bearing 62 adapted to receive the rolled end 63 of the lock 64 10 whereby said lock may be moved against the prong 12 when the latter is bent against the compressor, or held in substantially vertical position, as illustrated in Fig. 27 in dotted lines.

15 In Fig. 28 the compressor 14n has a slotted lip 65 on each end providing a bearing for the rolled end 66 of the lock 16n.

Figs. 29, 30, 31 and 32 show other modifications of locks and modified means of mounting the same. As shown in these figures, a lock 16o, 16p, 16r or 16s, respectively, is mounted along one longitudinal edge of the compressor adjacent each opening 15, and is arranged to co-operate with means on the other edge for holding the prong 12 tightly against the compressor whether 25 said prong is bent inwardly or outwardly of the opening.

It can readily be understood that the improved binding device illustrated in its various forms provides a very practical, efficient device capable 30 of ready manipulation, and one which will not injure the finger-nails of the user nor render the use of such devices objectionable.

Although exemplary embodiments of the improved fastener have been illustrated in the accompanying drawings and described in detail in the foregoing specification, it is to be understood that the various details of each fastener shown may be incorporated in other similar structures without departing from the spirit of the 40 invention or the scope of the appended claims.

I claim:

1. A fastener comprising, in combination, a compressor formed with an opening adjacent each end, a base having spaced prongs adapted to 45 extend one through each of said openings, a lip on each end of said compressor adjacent each opening, and yieldable means carried by said lips adapted to urge the portions of the prongs extending through said openings over against 50 the compressor.

2. A fastener comprising, in combination, an elongated compressor having reinforcing means on its longitudinal edges and transverse slots one adjacent each end, a base having spaced prongs 55 one on each end adapted to be passed through said slots and bent over against the compressor between said reinforcing means, lips on said compressor extending upwardly one adjacent each slot, said lips being outwardly of said slots and 60 having portions cut away to provide oppositely directed bearing lugs, and spring means mounted on said lugs adapted to overlie said slots and said bent over prongs to hold said prongs tightly against the compressor.

65 3. A fastener comprising, in combination, a compressor having a transverse slot adjacent each end, a base having spaced prongs adapted to be passed through said slots and be bent over the top of said compressor, retaining members hing- 70 edly mounted on said compressor one adjacent each end adapted to overlie the bent over portion of each of said prongs, and co-operating means on said retaining members and on said compressor for locking said members in place 75 over the prongs.

4. A fastener comprising, in combination, a compressor having a transverse slot adjacent each end, a base having spaced prongs adapted to be passed through said slots and bent over and against the top of said compressor, means 5 adjacent each end of said compressor for retaining said prongs in place over the compressor, and means for holding said means raised out of engagement with said prongs.

5. A fastener comprising, in combination, a 10 compressor formed with reinforcing means extending over its entire length and having a transverse slot adjacent each end, a base having spaced prongs adapted to be passed through said slots and bent over the top of said compressor, 15 and hinged means adjacent each end of said compressor for retaining the prongs in position on the compressor.

6. A fastener comprising, in combination, an elongated compressor formed with reinforcing 20 means on each of its longitudinal edges, the compressor having slots therein one adjacent each end, a base having spaced prongs adapted to be passed through said slots and bent over and against the top of said compressor between 25 said reinforcing means, and means hingedly mounted adjacent each end of said compressor adapted to co-operate with lugs on said reinforcing means for retaining the prongs in position.

7. In a paper fastener, the combination with a 30 compressor having a transverse slot adjacent each end, a base having spaced prongs adapted to be passed through papers and said transverse slots and bent flat on the compressor, substantially U-shaped retaining members pivotally 35 mounted on said compressor one adjacent each end, each of said retaining members being adapted to overlie the adjacent prongs for retaining it in place, and means on the compressor for engaging said retaining members to lock them in 40 place over said prongs.

8. In a paper fastener, the combination with a compressor having a transverse slot adjacent each end, a base having spaced prongs adapted to be passed through papers and said transverse slots 45 and bent over the compressor, a yieldable substantially U-shaped retaining member pivotally mounted adjacent each end of said compressor adapted to overlie the adjacent prongs, means on the compressor adapted to engage said retaining 50 members for locking said U-shaped members in place over the prongs, and means formed in said members to facilitate ready disengagement from said locking means.

9. In a paper fastener, the combination with 55 a compressor having a transverse slot adjacent each end, a base having spaced prongs adapted to be passed through papers and said transverse slots and bent over the compressor, a yieldable retaining member pivotally mounted on said 60 compressor adapted to overlie the adjacent prongs, means on the compressor adapted to engage said retaining members for locking said members in place over the prongs, means formed in said members to facilitate ready disengagement 65 from said locking means, and means on the retaining members adapted to engage said compressor to hold said retaining members out of locked position.

10. A fastener comprising, in combination, a 70 compressor having an opening adjacent each end, a base having spaced prongs adapted to extend through said openings and be bent inwardly towards each other over the top of the compressor, means adjacent each end of said compressor 75

movable into position to hold said prongs against said compressor, and means on said compressor inwardly of said openings adapted to have engagement with said prong holding means to retain them in place.

5. 11. A fastener comprising, in combination, a compressor having an opening inwardly of each end, a base having prongs adapted to extend through said openings and be bent outwardly 10 away from each other over the top of the compressor, means on the compressor adjacent each opening movable into position to hold said prongs against the compressor, and means on said compressor outwardly of the openings adapted to have engagement with said prong holding means to retain them in place.

12. A fastener comprising, in combination, a compressor having an opening adjacent each end, a base having prongs adapted to extend through 20 said openings and be bent over against the top of said compressor, means on the compressor adjacent each opening movable into a position to overlie the respective prong, and means on said compressor on each side of each of said openings 25 adapted to have engagement with said prong overlying means to retain them in position.

13. A fastener, in combination, an elongated compressor, a base having prongs adapted to be

bent over the top of said compressor, means adjacent each end of said compressor for retaining said prongs in place over said compressor, and means for holding said means raised out of engagement with said prongs.

5. 14. In a paper fastener, the combination with a compressor, a base having prongs adapted to be bent over said compressor, yieldable retaining members pivotally mounted on said compressor adapted to overlie the adjacent prongs, locking means to retain said retaining members in place over said prongs, and means on said retaining members to facilitate ready disengagement from said locking means.

10. 15. In a paper fastener, the combination with a compressor, a base having prongs adapted to be bent over said compressor, yieldable retaining members pivotally mounted on said compressor adapted to overlie the adjacent prongs, locking means to retain said retaining members in place over said prongs, means on said retaining members to facilitate ready disengagement from said locking means, and means on the retaining members adapted to engage said compressor to hold said retaining members out of locked position.

20. 25. ELMER L. ZWICKEL.
